March 12, 1929.

A. BÜHLER-ROSSBACH

1,705,141

GAME

Filed Aug. 27, 1928

Fig. 1.

Fig. 8.

Fig. 7.

Fig. 9.

Fig. 5.

Fig. 2.

Annie Bühlér-Rossbach

By Henry Orth Jr.

Atty.

Fig. 3. INVENTOR:

Fig. 6.

UNITED STATES PATENT OFFICE.

ANNIE BÜHLER-ROSSBACH, OF LUCERNE, SWITZERLAND.

GAME.

Application filed August 27, 1928, Serial No. 302,291, and in Switzerland August 10, 1928.

The subject matter of the present invention is a game, entitled the Peace and Society of Nations' game, which comprises a board to play on. In the midst of the board a symbolic field or picture of Peace is provided and subdivided into panels; the middle field is surrounded by marginal panels or pictures some of them symbolizing war and others peace. Further the game comprises a series of war 5 cards and a series of peace cards as well as a series of weapon cards. These cards serve for covering the panels or pictures on the board according to the rules of the game. Moreover a principal war card and a principal 10 peace card are provided as well as flags of the various nations forming at present the Society of Nations, blocks for mounting the flags thereon, counters and a die.

The accompanying drawing serves for explaining the subject matter of the present invention and shows a constructional example of the latter.

Figure 1 shows the game board.

Fig. 2 represents peace cards.

Fig. 3 represents war cards.

Fig. 4 represents a weapon.

Fig. 5 represents a main war card.

Fig. 6 represents a main peace card.

Fig. 7 represents a die.

Fig. 8 represents counters.

Fig. 9 represents a cork support and flags.

In the drawing 1 denotes the board of the game having in its center portion a field or picture 2 symbolizing peace and subdivided 35 into twelve panels. The peace picture 2 is surrounded by marginal pictures or panels of which the panels 3 indicate events of peace and the panels 4 events connected with war.

There are further provided a series of sixteen war cards 5, which contain a motto condemning war, and a series of sixteen peace cards 6, containing a motto praising peace. Further, a series of twelve weapon cards 7 bearing illustrations of different weapons, a 40 main war card 8 symbolizing and designated by Bellum and a main peace card 9 symbolizing and designated by Pax form parts of the game as well as thirty-five flags 10 of different nations forming the Society of Nations and cork blocks 11 of different colours for mounting the flags counters 12, a purse 13 for the latter and a die 14 the surfaces of which are designated with Pax, Bellum, Locarno, Geneva, The Hague, Red-Cross. 45

55 Two or more players (up to twelve) may take part in the game. The rules of the game are the following:

A leader is chosen amongst the players who displays the game board and covers the twelve panels of the center field or peace picture 2 by means of the twelve weapon cards 7, placing on every panel a weapon card with the picture face showing up. The flags, the other cards, the counters the blocks 11 and the die 14 are given in charge of the leader. He 55 hands one block 11 each to every player. Thereupon he distributes equal numbers of the counters to the players and retains a number of them in the main cash. Then he shuffles the remaining cards, distributes them 60 in equal numbers amongst the players and the game may be started. The aim of the game is to displace the weapon cards 7, which cover the peace panel or picture 2, according 65 to the rules of the game and thus to assist in the victory of peace over war. By this game the players get acquainted with the advantages of peace and the disadvantages of war by reading the motto printed on the respective cards which should always be read 70 in a loud voice. At the same time the players get acquainted with the insignia in the flags of the various nations and are induced to think internationally.

Every player holds the cards arranged in 85 order in his hand but in such a manner that they cannot be seen by the other players. Whoever has got the card 9 amongst his batch has to announce it and places this card openly 90 on the table before him. He is given three flags by the head player in order to plant them on his block 11, as well as three counters 12 from the purse 13 and he is entitled to remove one weapon card 7 from the central 95 field or peace picture 2 and to cover one of the war panels or pictures 4 partly with it placing the picture face of the card downward. This is repeated by every player who has had the chance to throw the die so that the "Pax" face shows up. The four war panels or pictures 4 need each time be covered only with three weapon cards 7 each and this has to be done consecutively. Therefore, only after one 100 war panel or picture 4 has been covered by three weapon cards 7 it is allowed to begin covering of the second war panel or picture 4. In the end all of the four war panels or pictures 4 must be covered with three weapon cards 7 each with their picture face downward 105 in order to exhibit the peace picture 2 now en- 110 tirely free from war, in the centre of which the block 11 provided with flags of the winner is planted to announce victory.

The one who has called the "Pax" card 5 and has received his reward begins to throw the die. If he throws one of the faces designated with Locarno, Geneva, Hague or Red Cross he turns to his neighbour to the right by saying: "I despise war". Thereupon he is 10 entitled to hand him a war card 5 from his batch by reading the motto imprinted on the war card 5 to be handed over in a loud voice; hereafter he again addresses the same neighbour by saying: "I desire peace". This neighbour 15 is now obliged to consent to this wish and to remit a peace card 6 from his batch to the petitioner. Now, the petitioner also reads the motto imprinted on this peace card 6 in a loud voice, he deposits it among the "Pax" 20 cards 9 and receives from the head player a further flag and a counter from the cash. Now, the neighbour to the right begins to play by throwing the die. Assuming that he again throws one of the faces mentioned above the 25 same game is repeated. If one of the players throws "Pax", the Pax card 9 together with the batch of peace cards 6 put down with it go to him, he receives three flags 10, three counters 12, is entitled to remove one of the 30 weapon cards 7 and to cover a war picture 4 with it, whereupon his neighbour to the right begins to play.

If however, one of the players throws Bellum, the player which has held the Bellum card 8 secretly in his batch is entitled to hand the same to the player which has thrown Bellum. The latter gives a flag 10 back to the head player and pays up one counter 12 to the cash. Then, he is obliged to deposit a war card 5 from his batch under the Bellum card 8 by reading off its motto. From now on, that is to say as soon as the Bellum card is displayed all war cards 5, exactly in the same way as for the Pax card 9, must be deposited underneath the Bellum card 8. The latter also, the same as the Pax card 9 changes its owner upon the unlucky throwing of Bellum, whereupon this player has to pay the fine as mentioned before.

It may also happen that one of the partners in the game is unable to comply with the request of a petitioner for a peace card 6 in that he only holds war cards 5 in his batch. He then must remit a flag 10 to the petitioner 55 and pay one counter 12 whereupon the batch of Bellum cards goes to him.

If on the contrary one of the players should be unable to remit a war card 5 to a petitioner for the Bellum batch as he holds but 60 peace cards 6, this lucky player is given the same reward as if he had throw Pax viz three flags, three counters, the right to remove one weapon card and to cover a war panel or picture therewith and besides he is entitled to the batch of Pax cards. Whoever is the owner of the batch of Bellum cards is only entitled to throw the die again after some other player has come in possession of this undesirable article.

The game is finished when all the flags are 70 used and consequently all the weapon cards 5 are removed from the central field or picture 2 and all the four war panels or pictures 4 are covered. Whoever has the most flags 75 planted on his block is the winner and is entitled to the cash and in the following game he will be appointed head player. He plants his block in the centre of the play board and the other blocks 11 with the flags thereon are grouped around it along the edge of the game 80 board 1, whereby a nice looking final effect is obtained.

I claim:

1. A game, comprising in combination, a 85 board having a center field symbolizing peace and subdivided into a plurality of panels, marginal panels, cards to be placed on the center field and removed to cover some of the marginal panels therewith, and a die having different markings, one of which entitles to 90 remove one of said cards at a time.

2. A game, comprising in combination, a 95 board having a center field symbolizing peace and subdivided into a plurality of panels, marginal panels some of them symbolizing war and others peace, a series of weapon cards to be placed on the panels of the center field and to be removed to cover the war pictures therewith, and a die having different markings, one of which entitles to remove one of 100 said cards at a time.

3. A game, comprising in combination, a 105 board having a center field symbolizing peace and subdivided into a plurality of panels, marginal pictures some of them symbolizing war, and others peace, a series of weapon cards to be placed on the panels of the center 110 picture and to be removed to cover the war panels therewith, a die having different markings, one of which entitles to remove one of said cards at a time, a series of war cards containing mottoes condemning war, and a series of peace cards containing mottoes praising peace.

4. A game, comprising in combination, a 115 board having a center field symbolizing peace and subdivided into a plurality of panels, marginal panels some of them symbolizing war and others peace, a series of weapon cards to be placed on the panels of the center 120 field and to be removed to cover the war panels therewith, a die having different markings, one of which entitles to remove one of said cards at a time, a series of war cards containing mottoes condemning war, a series 125 of peace cards containing mottoes praising peace, a principal war card designated "Bellum", and a principal peace card designated "Pax".

5. A game, comprising in combination, a 130 board having a center field symbolizing peace and subdivided into a plurality of panels, marginal panels, some of them symbolizing war and others peace, a series of weapon cards 5 to be placed on the panels of the center field and to be removed to cover the war panels therewith, a die having different markings, one of which entitles to remove one of said cards at a time, a series of war cards containing 10 mottoes condemning war, a series of peace cards containing mottoes praising peace, a principal war card designated "Bellum", and a principal peace card designated "Pax", a plurality of flags with insignias of 15 the nations forming the Society of Nations, and blocks for mounting the flags thereon.

6. A game, comprising in combination, a board having a center field symbolizing peace and subdivided into a plurality of panels, 20 marginal panels some of them symbolizing war and others peace, a series of weapon cards to be placed on the panels of the center field and to be removed to cover the war panels therewith, a die having different markings, a series of war cards containing mottoes 25 condemning war, a series of peace cards containing mottoes praising peace, a principal war card designated "Bellum", and a principal peace card designated "Pax", a plurality of flags with insignias of the nations forming 30 the Society of Nations, and blocks for mounting the flags thereon, and counters to be divided amongst the players.

7. A game, entitled the Peace and Society of Nations game in combination of a board 35 to play on having a smybolic central field subdivided into panels and marginal panels surrounding the same, some of these marginal panels symbolizing war and others peace, a series of war cards, a series of peace cards 40 and a series of weapon cards, all of which cards serving for covering the panels on the board according to the rules of the game, a principal war card, a principal peace card, flags with national insignia, blocks for plant- 45 ing the latter thereon, counters, and a die.

In testimony whereof I have signed my name to this specification.

ANNIE BÜHLER-ROSSBACH.